ENGINE STARTER

Glenn S. Thompson, Milwaukee, Wis., assignor to
 Briggs & Stratton Corporation, Milwaukee,
 Wis., a corporation of Delaware

Application May 4, 1945, Serial No. 591,921

11 Claims. (Cl. 74—7)

1

This invention relates to engine starters of the so-called automatic type having a pinion propelled along a power shaft to and from mesh with an engine gear by relative rotation between screw threaded parts on the pinion and an actuator therefor.

It is common practice in the art to drivingly connect the actuator to the power shaft for rotation therewith through a yieldable coupling embodying both torsional and endwise resiliency for cushioning rearward end thrust of the pinion during operation of the starter. Such a driving connection between the actuator and the power shaft has resulted in complicated structures in the past, and it is one of the objects of the present invention to provide a simple manner of effecting a splined driving connection between the actuator and a part fixed with respect to the power shaft which facilitates incorporation of endwise and torsional resiliency in said driving connection.

More specifically, it is one of the objects of this invention to provide an engine starter of the character described with a screw threaded actuator for the pinion having a sleeve extending axially therefrom and provided with a longitudinal slot to receive a driving abutment on the power shaft of the starter so that the actuator is splined thereto, and wherein the yieldable coupling is mounted on said sleeve between said driving abutment and a part of the actuator.

Another object of this invention resides in the provision of a novel driving connection between the pinion actuator and the power shaft which facilitates limiting axial motion of the actuator relative to the power shaft.

With the above and other objects in view which will appear as the description proceeds, this invention resides in the novel construction, combination, and arrangement of parts substantially as hereininafter described and more particularly defined by the appended claims, it being understood that such changes in the precise embodiment of the hereindisclosed invention may be made as come within the scope of the claims.

The accompanying drawing illustrates two complete examples of the physical embodiment of the invention constructed according to the best modes so far devised for the practical application of the principles thereof, and in which:

Figure 1 is a side elevational view of the starter of this invention having parts thereof broken away and shown in section to better illustrate details of construction with the pinion shown in its inoperative retracted position;

2

Figure 2 is a view similar to Figure 1 showing the parts in the positions they occupy with the pinion in its operative projected engine cranking position;

Figure 3 is a fragmentary perspective view of a portion of the starter illustrating the manner in which the driving connection is established between the pinion actuator and the power shaft; and

Figure 4 is a fragmentary perspective view of a portion of a slightly modified pinion actuator illustrating another manner of limiting axial motion of the actuator relative to the power shaft.

Referring now more particularly to the accompanying drawing in which like numerals indicate like parts, the numeral 5 generally designates the starter of this invention and which includes a tube 6 telescoped over the power shaft 7 of the starting motor 8. The tube 6 unitarily mounts all of the starter parts and is adapted to be anchored to the power shaft 7 of the starting motor, in a manner to be later described, so as to form in effect a part of the power shaft.

The customary drive pinion 9 is freely rotatable and slidable along the inner end portion of the tube 6 from an inoperative retracted position, shown in Figure 1, to an operative projected engine cranking position, shown in Figure 2, in which it meshes with an engine gear 10. The operative cranking position of the pinion is defined by the customary pinion stop collar 11 on the inner extremity of the tube adjacent to the starting motor.

The pinion is provided with an externally screw threaded sleeve 12 projecting axially from the pinion toward the outer end of the power shaft and which cooperates with an externally threaded pinion actuator 13 in the customary manner to produce propulsion of the pinion to and from mesh with the engine gear upon rotation of the actuator relative to the pinion and to drivingly connect the pinion to the actuator for rotation therewith through the interengaging screw threads of said parts upon interference with propulsion of the pinion toward mesh with the engine gear.

The manner in which the screw threaded pinion actuator is drivingly connected to the power shaft constitutes one of the features of this invention and for this purpose the actuator is provided with a sleeve 14 encircling the power shaft and extending axially therealong in a direction away from the pinion 9 and toward the outer free end of the power shaft. Near the outer extremity of the sleeve 14 circumferentially spaced

slots 15 are provided in the sleeve so as to produce spaced drive fingers 15' on the sleeve at the outer extremity thereof.

A collar 16 telescoped over the bifurcated end of the sleeve has circumferentially spaced driving abutments 17 projecting radially inwardly into its bore and entering the slots 15 of the bifurcated end of the sleeve for cooperation with the drive fingers 15' in the provision of a splined driving connection between the actuator and collar.

The collar 16 also serves to anchor the tube 6 to the power shaft so that the tube forms a part thereof. For this purpose a set screw 18 is provided having a shank threaded into aligned holes in the collar and sleeve with a reduced end portion 19 entering a suitable well in the side of the shaft to lock the collar and tube to the power shaft.

The forward end of the collar forms substantially a cylindrical skirt 20 which telescopes over the bifurcated end of the sleeve 14 a distance such that the drive slots thereof are enclosed by the skirt. The forward edge of the skirt 20 also forms an annular abutment which cooperates with abutments 21 formed by the ends of the threads on the actuator adjacent to the collar to define an axial space for a bank of cupped spring washers 22 encircling the sleeve 14 and confined between said abutments on the actuator and skirt 20.

These spring washers tend to expand and urge the actuator axially away from the collar 16 and inwardly along the power shaft. Such forward axial motion of the actuator is limited, however, by lugs 23 struck outwardly from the extremities of the drive fingers during assembly of the parts into the slots 15 and engaging over the outer end of the collar 16.

The spring washers 22 serve as cushioning means to yieldingly absorb motion of the actuator toward the collar such as occurs as the result of end thrust translated to the actuator from the pinion during cranking of the engine as illustrated in Figure 2. Thus, it will be seen that the washers in yielding axially provide a degree of torsional resiliency in the driving connection between the power shaft and pinion to effectively protect the starter against shock.

Because of the fact that the ends of the threads on the actuator 13 adjacent to the collar 16 provide one of the abutments against which the stacked spring washers 22 engage, it is possible for the pinion to strike against the innermost pair of spring washers upon retraction of the pinion to its inoperative position. This provides for cushioning of the pinion at the time it is thrown out of mesh with the engine gear upon starting of the engine.

Attention is also directed to the fact that because the skirt 20 on the collar 16 is directed forward sufficiently far over the bifurcated extremity of the actuator sleeve 14 so as to overlie an unbroken circumferential portion of the sleeve, that the inner peripheral portion of the spring washers are prevented from entering the spaced slots 15 in the end of the sleeve. Jamming of the starter parts is thus precluded.

In the modification illustrated in Figure 4, axial motion of the pinion actuator inwardly along the tube away from the collar is limited by a novel stop formed by a detachable spring ring 25, snapped over the bifurcated extremity of the sleeve 14 and sprung into notches 26 cut into the side edges of the drive fingers 15' adjacent to

their outer extremity. Hence, the spring ring 25 is brought to bear against the outer face of the collar in the same manner as the lugs 23, but the detachability thereof enables ready disassembly of the starter parts for inspection or replacement as required.

From the foregoing description taken in connection with the accompanying drawing, it will be readily apparent to those skilled in the art that the novel driving connection between the power shaft and pinion actuator lies wholly to one side of the cushioning means by which endwise and torsional resiliency is achieved and that by reason of this fact compactness and simplicity of construction is assured.

What I claim as my invention is:

1. In an engine starter of the type having a pinion propelled along a power shaft into and out of mesh with an engine gear by relative rotation between screw threaded parts on the pinion and an actuator for the pinion slidably mounted on the power shaft, a driving connection between the power shaft and actuator comprising: a collar fixed on the power shaft and having circumferentially spaced longitudinal grooves in its bore; drive fingers projecting axially from the actuator and received within said grooves in the bore of the collar to provide a splined driving connection between the actuator and the collar permitting a degree of axial movement of the actuator toward the collar in response to end thrust developed as the starter picks up the load of the engine; and resilient cushioning means encircling the actuator wholly to one side of said splined driving connection and reacting between the actuator and collar to yieldingly resist said thrust of the actuator during operation of the starter.

2. In an engine starter of the type having a pinion propelled along a power shaft into and out of mesh with an engine gear by relative rotation between screw threaded parts on the pinion and an actuator for the pinion slidably mounted on the power shaft, a driving connection between the power shaft and actuator comprising: a collar fixed on the power shaft and having circumferentially spaced longitudinal grooves in its bore; drive fingers projecting axially from the actuator and received within said grooves in the bore of the collar to provide a splined driving connection between the actuator and the collar permitting a degree of axial movement of the actuator toward the collar in response to end thrust developed as the starter picks up the load of the engine; and resilient cushioning means reacting between the actuator and collar to yieldingly resist said thrust of the actuator during operation of the starter, said cushioning means being disposed on an unbroken circumferential portion of the actuator and wholly to one side of the collar.

3. In an engine starter of the type having a pinion propelled along a power shaft into and out of mesh with an engine gear by relative rotation between screw threaded parts on the pinion and an actuator for the pinion slidably mounted on the power shaft, a driving connection between the power shaft and actuator comprising: a sleeve on the actuator extending axially therefrom in a direction away from the pinion; circumferentially spaced drive fingers on the end of said sleeve remote from the pinion; circumferentially spaced fixed abutments on the power shaft engaged between said drive fingers on the sleeve to provide a splined driving connection be-

tween the power shaft and the actuator; an annular skirt projecting axially from said abutments with its free end facing the actuator and telescoped over the drive fingers to cover at least the inner ends of the same; and cushioning means on the sleeve reacting between said end of the skirt and a part on the actuator for yieldingly resisting axial motion of the actuator away from the pinion toward the abutments.

4. In an engine starter of the type having a pinion propelled along a power shaft into and out of mesh with an engine gear by relative rotation between screw threaded parts on the pinion and an actuator for the pinion slidably mounted on the power shaft, a driving connection between the power shaft and actuator comprising: a sleeve on the actuator extending axially therefrom in a direction away from the pinion; circumferentially spaced drive fingers on the end of said sleeve remote from the pinion; circumferentially spaced fixed abutments on the power shaft engaged between said drive fingers on the sleeve to provide a splined driving connection between the power shaft and the actuator; an annular skirt projecting axially from said abutments with its free end facing the actuator and telescoped over the drive fingers to cover at least the inner ends of the same; cushioning means on the sleeve reacting between said end of the skirt and a part on the actuator for yieldingly resisting axial motion of the actuator away from the pinion toward the abutments; and interengaging parts on the sleeve and said abutments for limiting axial motion of the actuator away from said abutments.

5. In an engine starter of the type having a pinion propelled along a power shaft into and out of mesh with an engine gear by relative rotation between screw threaded parts on the pinion and an actuator for the pinion slidably mounted on the power shaft, a driving connection between the power shaft and actuator comprising: a collar fixed on the power shaft remote from the pinion, said collar having a longitudinal groove cut in its bore and extending to the opposite ends of the collar; a sleeve on the actuator extending axially therefrom toward the collar; a drive finger on the extremity of the sleeve remote from the pinion received within said longitudinal groove of the collar to provide a splined driving connection between the collar and actuator, the drive finger extending entirely through said groove with its outer extremity disposed exteriorly of the end of the collar opposite the actuator; a lug on said extremity of said drive finger struck therefrom over said end of the collar remote from the pinion to limit axial movement of the actuator away from the collar; and resilient cushioning means reacting between the actuator and the collar and encircling said sleeve inwardly of the drive finger for yieldingly resisting axial thrust of the actuator toward the collar during operation of the starter.

6. In an engine starter of the type having a pinion propelled along a power shaft into and out of mesh with an engine gear by relative rotation between the pinion and power shaft; an actuator for the pinion slidably mounted on the power shaft and having external screw threads thereon cooperating with an internally screw threaded part on the pinion so that rotation of the actuator relative to the pinion effects axial motion of the pinion along the power shaft; a sleeve on the actuator encircling the power shaft and extending axially therealong away from the

pinion, said sleeve having circumferentially spaced longitudinal slots in its extremity remote from the pinion; a collar received on said sleeve and substantially enclosing the slots thereof; circumferentially spaced driving abutments in the bore of the collar received in said slots of the sleeve to provide a substantially enclosed splined driving connection between the collar and actuator; means rigidly anchoring said collar onto the power shaft so that rotation of the shaft is translated into rotation of the actuator; and cushioning means received on said sleeve at the pinion side of the collar and reacting between the actuator and collar to yieldingly resist axial thrust of the actuator toward the collar during operation of the starter.

7. In an engine starter of the type having a pinion propelled along a power shaft into and out of mesh with an engine gear by relative rotation between screw threaded parts on the pinion and an actuator for the pinion slidably mounted on the power shaft, a driving connection between the power shaft and actuator comprising: a sleeve on the actuator encircling the power shaft and extending axially therealong away from the pinion, said sleeve having a longitudinal slot in its extremity remote from the actuator; a collar received on said sleeve; a driving abutment extending substantially radially into the bore of the collar and entering the slot in the sleeve so as to provide a splined driving connection between the collar and actuator; means anchoring the collar to the power shaft so that the actuator rotates therewith; a split spring ring encircling the sleeve at the side of the collar remote from the pinion and sprung into notches in the sleeve so as to form a stop thereon engaged by the collar to limit axial motion of the actuator away from the collar; and cushioning means received on said sleeve and reacting between the collar and an abutment on the actuator to yieldingly hold the actuator and collar axially separated and for yieldingly resisting thrust of the actuator toward the collar developed during operation of the starter.

8. In an engine starter of the type having a pinion propelled along a power shaft into and out of mesh with an engine gear by relative rotation between the pinion and power shaft; an actuator for the pinion slidably mounted on the power shaft and including an externally screw threaded forward portion and an unthreaded sleeve extending axially rearwardly from the threaded portion of the actuator, the screw threads on said forward portion terminating in abrupt shoulders at the junction between the sleeve and forward threaded portion of the actuator; a sleeve on the pinion having internal screw threads for cooperation with the screw threaded portion of the actuator so that rotation of the actuator relative to the pinion effects axial motion of the pinion along the power shaft, said actuator sleeve having circumferentially spaced longitudinal slots in its extremity remote from the pinion providing drive fingers; a collar received on the actuator sleeve at the slotted end portion thereof; circumferentially spaced driving abutments in the bore of the collar received in said slots of the actuator sleeve so as to cooperate with said drive fingers in the provision of a splined driving connection between the collar and actuator; means securing said collar to the power shaft so that rotation of the shaft is translated into rotation of the actuator; and cushioning means received on said actuator sleeve between the abutments formed by the ends

of the actuator threads and said collar and reacting therebetween to yieldingly resist axial thrust of the actuator toward the collar during operation of the starter, said pinion sleeve having an axial length such as to permit engagement thereof with said cushioning means upon relative rotation between the actuator and pinion in a direction to retract the pinion to an inoperative position with respect to the engine gear whereby the cushioning means absorbs the shock of pinion retraction.

9. In an engine starter of the type having a pinion propelled along a power shaft into and out of mesh with an engine gear by relative rotation between the pinion and power shaft: a substantially tubular actuator for the pinion having external screw threads on its forward portion with the root diameter of said threads substantially equal to the diameter of the unthreaded rear portion of the actuator; a sleeve on the pinion having internal screw threads for cooperation with the threads on the actuator so that rotation of the actuator relative to the pinion effects axial motion of the pinion along the power shaft; a collar fixed on the power shaft and having circumferentially spaced longitudinal grooves in its bore to provide driving abutments therebetween; drive fingers on the unthreaded rear portion of the actuator and received within said grooves in the bore of the collar for cooperation with the drive abutments thereon in the provision of a splined driving connection between the actuator and collar permitting a degree of axial movement of the actuator toward the collar in response to end thrust developed as the starter picks up the load of the engine; and resilient cushioning means received on the unthreaded rear portion of the actuator in a position to be engaged by the pinion sleeve during axial motion of the pinion toward the collar to its inoperative retracted position for absorbing the shock of pinion retraction, said cushioning means reacting between the actuator and collar to yieldingly resist said thrust of the actuator during operation of the starter.

10. In an engine starter of the type having a pinion propelled along a power shaft into and out of mesh with an engine gear by relative rotation between screw threaded parts on the pinion and an actuator for the pinion slidably mounted on the power shaft, a driving connection between the power shaft and actuator, comprising: circumferentially spaced abutments on the power shaft remote from the pinion; a sleeve on the actuator extending outwardly from one end thereof toward said shaft abutments; circumferentially spaced

abutments on said sleeve engaged with the shaft abutments to provide a splined driving connection between the shaft and actuator allowing a degree of axial motion of the actuator along the shaft; a stop on the actuator located between the pinion and said shaft abutments; means on the shaft providing a stop so located along the shaft as to lie between the actuator stop and said actuator and shaft abutments; and resilient cushioning means encircling the actuator inwardly of said splined driving connection and confined between said actuator and shaft stops for yieldingly resisting axial motion of the actuator toward the shaft abutments.

15. 11. In an engine starter of the type having a pinion propelled along a power shaft into and out of mesh with an engine gear by relative rotation between screw threaded parts on the pinion and an actuator for the pinion slidably mounted on the power shaft, a driving connection between the power shaft and actuator, comprising: circumferentially spaced abutments on the power shaft remote from the pinion; a sleeve on the actuator extending outwardly from one end thereof toward said shaft abutments; circumferentially spaced abutments on said sleeve engaged with the shaft abutments to provide a splined driving connection between the shaft and actuator allowing a degree of axial motion of the actuator along the shaft; a stop on the actuator located between the pinion and said actuator abutments; means on the shaft encircling said shaft and sleeve abutments to substantially enclose the same, said means having a part providing a stop so located along the shaft as to be positioned between the actuator stop and said sleeve and shaft abutments; and resilient cushioning means encircling the actuator inwardly of said splined driving connection and confined between said actuator and shaft stops for yieldingly resisting axial motion of the actuator toward the shaft abutments.
